ELEVATING PLATFORM TRUCK

Frank M. Reynolds and Delmar R. Conrad,
San Gabriel, Calif.

Application April 25, 1945, Serial No. 590,172

4 Claims. (Cl. 187—9)

1

This invention relates to a device for transporting production parts and the like to and from stations or machines within industrial plants.

It is the general object of our invention to provide a simple and convenient device for the purpose specified. More particularly it is the object to provide a device which may be quickly adjusted vertically to the end that goods may be loaded thereon or discharged therefrom at any required elevation.

Other objects as well as the many advantageous features of our invention will be readily understood from the following detailed description, and drawings are hereto annexed in which a preferred form of the invention is illustrated. In the drawings:

Fig. 1 is a side view of the device of our invention;

Fig. 2 is a substantially corresponding view showing the mechanism thereof vertically fully extended;

Fig. 3 is a plan view showing only the lowermost portion of the device;

Fig. 4 is a plan view of the bottom section of the elevating mechanism;

Fig. 5 is a substantially corresponding side view thereof;

Figs. 6 and 7 are similar views of the intermediate sections of the elevating mechanism; and

Fig. 8 illustrates a portion of the gear connections operating this mechanism.

The structure of our invention, in the form illustrated in the drawings comprises a rectangular base 1, which at the center is provided with perforations adapted to receive a pivot 2, and the latter serves to support the elevating mechanism of the invention, as will now be fully described. As both sides of the device may be and preferably are exactly alike, it is to be understood that a detailed description of any parts at one side thereof equally pertains to similar parts at the other side.

An extendable structure, in the form of a lazy tongs arrangement rises from the base 1. This arrangement is composed of a series of interconnected frames, the two first, or lowermost of which are shown to comprise, respectively, links 3, 4 and 5, 6, all of which are hung to swing on the pivot 2, as best shown in Figs. 3 and 4. The links are shown mounted on hubs 7 in order to maintain them in proper spaced relation to each other and so as to provide better bearing surfaces on the pivot 2. Spacing members 8, 9 are made with trunnions seated in these links at the outer

ends thereof. Finally, diagonal braces 10, 11 and 12, 13 span the spaces between the link combinations so as to form said link combinations into the aforementioned two lowermost frames.

A series of intermediate frames rise from the two bottom frames and, as these frames may all be exactly alike, only the frames directly connected to the bottom frames are described in detail. As indicated in Figs. 1 and 2, the links are made with aligned perforations through which extend pins or rivets 14, 15, pivotally to support the two frames 20, 21 and hubs 20¹, 21² are placed on these pins to maintain the links of the frames 20, 21 properly spaced apart. These frames are nearly twice as long as the bottom frames but may otherwise be similarly constructed and the opposed inner surfaces of the frames 20 are also similarly cross braced, see also Figs. 6 and 7. At one end of each of said frames 20, 21 may be mounted rollers 22, 23 to ride on the base 1, and they are pivotally joined at the center, as indicated at 24.

The two next following frames are similarly joined at 25, 26, near the ends of the frames 3 and 4, 5, 6, and any required number of intermediate frames may be added in like manner. The two top frames 27, 28 may be like the bottom frames, except that they are not extended to support trunnion members, but are shortened and aligned with the ends of the intermediate frames. The inner ends of the top frames are hung on a pivot 29 of the top platform 30, and rollers 31, 32 may be provided at the outer ends of the frames directly below these top frames to ride along the undersurface of the top platform.

The mechanism employed to operate the structure above described terminates in four screws 40, which are seated in sockets of bushings 46, see Fig. 8. As these four screws and the parts directly associated therewith may be exactly alike, the same reference numerals are applied to all of them. Shafts 41 are journaled in the base to carry bevel gears 42, and the latter are permanently in mesh with gears 43 of the screws. The two shafts are suitably interconnected, as by a chain 44 riding on sprockets 45 of the two shafts, and one of the shafts, or both, may be shaped for connection to suitable rotating means (not shown).

As stated, the screws 40 are seated to rotate in the bushings 46, which in turn are rotatable on the shafts 41, see also Fig. 6, in order that the screws may be free to swing inward as they gradually move the frames of the lazy tongs arrangement to elevate the platform 30. It is important

to note that this inward movement of the screws is so timed relative to the upward movement of the platform and intermediate frames that the outer ends of all these parts clear the inwardly moving screws as they rise to pass the upper ends thereof.

When the base is set on wheels or casters, substantially as indicated in the drawings, it is seen that a floor truck is provided, on which goods may be conveniently loaded and transported from place to place. Also that the platform may be raised to any desired height, within the limits of movement of the lazy tongs arrangement, and that diagonal braces of all the frames combine to provide a substantially rigid structure, free from side sway. The device may therefore be depended upon safely to support material to be transported, within the calculated load carrying capacity of the device.

We claim:

1. In a device for transporting goods, a base platform, a storage platform, series of frames intermediate said platforms combining to form a lazy tongs arrangement therebetween, transverse shafts on said base platform, threaded stems vertically hung to swing on said shafts, elements in the outer ends of the lowermost of said frames riding on the threads of the stems, gear connections between said shafts and stems for rotating the latter thereby to extend and collapse said lazy tongs arrangement.

2. In a device for transporting goods, a base platform, a pivot centrally traversing said platform, two frames hung to swing on said pivot and extending therefrom right and left, a storage platform, two frames similarly hung on the underside thereof, series of frames intermediate said upper and lower sets of frames combining therewith to form a lazy tongs arrangement, transverse shafts in said base platform parallel with said central pivot, threaded stems vertically hung on said shafts, elements in the outer ends of the lowermost set of frames riding on the threads of said stems, and gear connections between said shafts and stems for rotating the latter thereby to

extend or collapse said lazy tongs arrangement.

3. In a device for transporting goods and the like, a base platform, a storage platform, series of frames intermediate said platforms combining to form a lazy tongs arrangement therebetween, transverse shafts on said base platform, threaded stems vertically hung to swing on said shafts, elements in the outer ends of the lowermost of said frames riding on the threads of said stems, gear connections between said shafts and stems for rotating the latter thereby to extend or collapse said lazy tongs arrangement, and braces rigidly interconnecting the side members of said frames.

4. The combination with a base platform and a storage platform, of a lazy tongs arrangement therebetween comprising series of pivotally interconnected frames, each frame consisting of double side members held spaced apart by hubs, cross braces rigidly interconnecting the opposed inner surfaces of said side members, threaded stems rising from the corners of said base platform and riding in the spacing hubs at the ends of the side members of the lowermost frames, and means for rotating said stems thereby to operate said arrangement of frames to raise and lower said storage platform.
